UNITED STATES PATENT OFFICE

153,351

DESIGN FOR A WALL DISPENSER

Robert Grocoff, New York, N. Y.

Application April 3, 1947, Serial No. 138,142

Term of patent 3½ years

(Cl. D33—18)

To all whom it may concern:

Be it known that I, Robert Grocoff, a citizen of the United States, residing in New York, New York, in the county of New York and State of New York, have invented a new, original, and ornamental Design for a Wall Dispenser, of which the following is a specification, reference being had to the accompanying drawing, forming part thereof.

The figure is a perspective view of a wall dispenser, showing my new design.

I claim:

The ornamental design for a wall dispenser, as shown.

ROBERT GROCOFF.
